FIG. 1 is a front elevational view of a tire air valve mini helmet cover showing my novel design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top perspective view of a tire air valve mini helmet cover of the present invention; and,

FIG. 8 is a bottom perspective view of a tire air valve helmet cover of the present invention.
